UNITED STATES PATENT OFFICE.

DAVID DORWARD, OF SAN FRANCISCO, CALIFORNIA, ASSIGNOR TO THE RISDON IRON AND LOCOMOTIVE WORKS, OF SAME PLACE.

TUBULAR METALLIC POLE.

SPECIFICATION forming part of Letters Patent No. 470,153, dated March 1, 1892.

Application filed August 8, 1891. Serial No. 402,114. (No model.)

To all whom it may concern:

Be it known that I, DAVID DORWARD, a citizen of the United States, and a resident of the city and county of San Francisco, State 5 of California, have invented certain new and useful Improvements in Tubular Metallic Poles; and I do hereby declare that the following is a full, clear, and exact description of the same.

10 My invention relates to the construction of metallic poles intended especially to support elevated electric conductors, such as telegraph, telephone, and electric-light wires. The desirability of substituting metallic for 15 wooden poles is universally conceded, not only from their great durability, but because they can be given an ornamental appearance.

The object of my invention is to provide a sectional metallic pole of exceedingly cheap 20 and simple construction, the sections of which can be easily put together and permanently secured, so that the pole, while it is manufactured and transported in sections, will when in place be practically a pole formed 25 in one piece.

The invention consists principally in the improved manner of connecting and securing the sections together, and also in certain details of construction, which need not be specifically mentioned here, but which are fully 30 hereinafter described, as well as shown in the accompanying drawings, in which—

Figure 1 is an elevation of the pole complete. Fig. 2 is a vertical section at one of 35 the joints. Fig. 3 is a section on the line X X of Fig. 2.

My improved pole is composed of any desired number of metallic tubular sections. I have shown in the drawings three of such sections intended when put together to form a 40 pole of about thirty feet in height.

Referring to Fig. 2, which illustrates by a vertical section the union of any two of these tubular parts, A represents one section of tubing, and B an adjoining section above. Supposing the section A to be composed of a 45 length of six-inch tubing, the adjoining section is preferably made from five-inch tubing.

A rivet *a* is driven transversely through the tube A and firmly secured, forming a stop 50 upon which the tube B rests when in place. Formed with the tube, or preferably shrunk upon it, is a ring *b*, which closes the annular space between the two tubes at the bottom. Into the upper part of this space are driven 55 wedges or keys *c*, in order to preserve the two tubes in proper relative position and keep the tube B vertical. Three of these keys are shown in the drawings, but as many may be used as may be necessary, according 60 to the size of the respective tubes. The annular space between the tubes is then tightly packed or calked, preferably with a composition which forms what is known as a "rust-joint," and is composed of iron filings or bor- 65 ings, sal-ammoniac, and water. When this has set, the two tubes will be so firmly connected as to form practically one continuous tubular pole. The joint is covered and concealed by an ornamental sleeve or thimble. 70 I prefer to use the rust-joint described for a packing between the two tubes; but other substances or compositions may be employed instead, such as melted sulphur or lead.

The advantages of my device lie principally 75 in its extreme simplicity, cheapness of construction, and durability. I avoid the necessity of forming threads or any of the other expensive methods of construction now employed, and am thus enabled not only to reduce the cost, but to render it much easier to 80 connect the tubes when placing the pole in position.

While I have described my invention as practically adapted to tubular poles for supporting electrical conductors, I do not confine myself to such use, as the method of jointing the sections may be employed in the connection of the tubes to be used for other purposes.

Having described my invention, I claim— 90

1. In combination, the tube A, having a stop, the tube B of smaller diameter inserted therein, a ring closing the bottom of the annular space between the two tubes, and a packing in the space above said ring, sub- 95 stantially as and for the purposes set forth.

2. The combination of the tube A, the tube B, inserted therein and having the external ring *b* at its base, the keys *c*, and a packing between the tubes, substantially as set forth.
5. 3. The combination, with the tube A, of the inserted tube B, and the transverse rivet *a*, forming a stop, substantially as set forth.

In testimony whereof I have hereunto affixed my signature, in the presence of two witnesses, this 31st day of July, 1891.

DAVID DORWARD.
